DESCRIPTION

FIG. 1 is a perspective view of the floor section module for entrance floor, with a single floor section module shown in an elevated position.

FIG. 2 is a top view of the floor section module for entrance floor of FIG. 1.

FIG. 3 are front and rear views of the floor section module for entrance floor of FIG. 1.

FIG. 4 are left and right side views of the floor section module for entrance floor of FIG. 1.

FIG. 5 is a perspective view of the floor section module for entrance floor of FIG. 1; and,

FIG. 6 is a bottom view of the floor section module for entrance floor of FIG. 1.

The broken lines shown throughout these figures are for illustrative purposes only and form no part of the claimed design.
